ILLUMINATOR

David J. Biller, St. Louis, Mo., assignor to Day-Brite Reflector Company, St. Louis, Mo., a corporation of Missouri

Application February 16, 1934, Serial No. 711,493

4 Claims. (Cl. 240—78)

This invention relates principally to devices for illuminating the sides of passageways, particularly for illuminating book stacks, stock bins, filing cabinets and the like which are commonly arranged on either side of passageways. The principal object of the present invention is to provide a simple and economical illuminator which will provide an even dispersion of the light from top to bottom of the sides of the passageway, and which will minimize glare. The invention consists in the illuminating device and in the construction, combinations and arrangements of parts hereinafter described and claimed.

In the accompanying drawing, which forms part of this specification and wherein like symbols refer to like parts wherever they occur,

Fig. 1 is a view, partly in vertical section and partly in side elevation, of an illuminating device embodying my invention, the device being shown attached to an outlet box mounted in a ceiling, dispersion and reflection of the light rays from typical points on the reflector shade and disk being indicated by dotted lines;

Fig. 2 is a horizontal section on the line 2—2 in Fig. 1;

Fig. 3 is a horizontal section on the line 3—3 in Fig. 1;

Fig. 4 is a fragmentary plan view of the middle portion of the reflector disk;

Fig. 5 is a fragmentary plan view of the middle portion of the reflector shade;

Fig. 6 is a fragmentary vertical section, showing the manner of fastening the disk reflector to the outlet box; and

Fig. 7 is a vertical cross-section through a portion of a library stack room with the illuminating device sustained by the ceiling above the passageway between the book stacks, the dotted lines indicating the various directions in which the light rays are dispersed.

Referring to the accompanying drawing, my invention is shown in connection with a source of light comprising an electric light bulb A mounted in a suitable socket B disposed beneath a suitable outlet box C that is attached to the ceiling of a library stack room midway of the passageway D formed by two lines of book stacks E.

The light from the electric light bulb is distributed by means of a reflector disk F located above the light bulb A and a reflector shade G that surrounds said light bulb below said reflector disk. The reflector disk F is of greater diameter than the reflector shade G; and the lower surface of said reflector disk and the inner and outer surfaces of said reflector shade are provided with

a suitable light reflecting covering such as white porcelain enamel.

The reflector disk F is removably secured flatwise to the underside of the outlet box C by means of diametrically opposed screws 1. The screws 1 are located outside of the reflector shade G and extend upwardly through openings 2 in the reflector disk F and are threaded into inwardly extending ears 3 at the lower edge of the outlet box C. The screw receiving openings 2 in the reflector disk F are in the form of keyhole slots so as to permit said disk to be attached to and detached from the outlet box C without removing the screws 1.

The reflector shade G is removably secured flatwise to the underside of the reflector disk F by means of diametrically opposed screws 4 that extend upwardly through openings 5 in the top of said reflector shade and are threaded into said reflector disk. The openings 5 are in the form of keyhole slots so as to permit the reflector shade to be detached from the reflector disk without removing the screws 4.

The light socket B has a base portion 6 located within the upper portion of the reflector shade G and an upper portion 7 of reduced diameter that extends upwardly through central openings 8 and 9 provided therefor in the top of said shade and in the reflector disk F. The enlarged base portion 6 of the socket B is removably secured to the underside of the top wall of the reflector shade G by means of diametrically opposed bolts 10. These bolts extend upwardly through registering holes provided therefor in the base portion of the socket and in the top of the reflector shade and have nuts 11 threaded on their upper ends and bearing against the top of said shade. The bolt holes 12 in the top of the reflector shade are located intermediate between the keyhole slots 5 therein; and the socket receiving opening 9 in the reflector disk is enlarged, as at 9a, to accommodate the nuts 11 for the bolts 10.

By the arrangement above described, the illuminator may be readily mounted on and dismounted from the outlet box. To install the illuminator, the socket B is secured to the top of the reflector shade G by means of the bolts 10, the reflector disk F is secured to the bottom of the outlet box by means of the screws 1. The electric wires are then fastened to the light socket, after which the reflector shade is secured to the underside of the reflector disk by means of the screws 4. In dismounting the illuminator, the reflector shade and the reflector disk may be removed without removing the fastening screws 1 therefor by bringing the heads of said screws into

register with the enlarged ends of the keyhole slots 2.

The reflector shade comprises a downwardly opening bell-shaped body portion having a lower portion 13 of relatively steep taper, an upper portion 14 of slightly less width and slightly steeper taper, and a relatively narrow intermediate portion 15 which tapers less steeply than the wider upper and lower portions. The upper portion 14 is provided with four circumferentially spaced openings 16 that are separated by pairs of diametrically opposed webs 17 located respectively longitudinally of and at right angles to the axis of the aisle.

With the illuminator mounted on the ceiling above the passageway, as shown in Fig. 7, some of the rays from the incandescent light bulb A are projected downwardly and outwardly from the mouth of the reflector shade G, the dash lines indicating the upper limit of the rays issuing directly or by reflection from the mouth of said shade. Thus the upper shelves are not illuminated by these rays. As shown in dotted lines in Figs. 1 and 7, some of the light rays are projected outwardly through the openings 16 in the upper portion 14 of the reflector shade and serve to light the uppermost shelves of the book stacks. Other of the rays projected through the openings 16 strike the underside of the reflector disk and are deflected downwardly and outwardly toward intermediate shelves. Some of the light rays reflected by the reflector disk are again reflected at various oblique angles by the differently tapered outer sides of the reflector shade and thus result in a further dispersion of the light over the upper book shelves. As the light rays are dispersed around the entire periphery of the illuminator, they extend longitudinally and angularly as well as transversely, so that long stretches of the sides of the passageway are illuminated by a single fixture.

The above illuminator produces an even dispersion of the light from top to bottom of the sides of the passageway and it minimizes the glare. It also secures a maximum dispersion of the light rays lengthwise of said sides, thus permitting a maximum spacing of the illuminators.

What I claim is:

1. An illuminator comprising an incandescent light bulb, a socket therefor, an outlet box, a reflector disk removably secured flatwise to the underside of said outlet box, a reflector shade surrounding said bulb and having a flat top wall which is removably secured flatwise to the un-

derside of said reflector disk, and means for removably securing said socket to the underside of the top wall of said reflector shade.

2. An illuminator comprising an incandescent light bulb, a socket therefor, an outlet box, a reflector disk secured to the underside of said outlet box, a reflector shade surrounding said bulb and removably secured to the underside of said reflector disk, and means for removably securing said socket to the top of said reflector shade, said disk and said shade being provided with central openings through which the upper portion of said socket extends, the upper portion of said reflector shade being provided with a series of circumferentially spaced openings, the lower portion having a relatively steep taper and the portion intermediate between said openings and said lower portion having a slightly steeper taper.

3. An illuminator of the overhead exposed bulb type comprising a depending light bulb, a socket therefor, and a downwardly opening bell-shaped shade of opaque material surrounding said bulb and having interior and exterior light reflecting surfaces, said shade having a flat top wall for sustaining said socket, a lower portion of relatively steep taper and an intermediate portion which tapers less steeply than said lower portion, said intermediate portion being spaced below said flat top wall and rigidly connected to the outer edge thereof by a series of circumferentially spaced webs.

4. An illuminator of the overhead exposed bulb type comprising a depending light bulb, a socket therefor, and a downwardly opening bell-shaped shade of opaque material surrounding said bulb and having an interior light reflecting surface, said shade having a flat top wall for sustaining said socket, a lower portion of relatively steep taper and an intermediate portion which tapers less steeply than said lower portion, said intermediate portion being spaced below said flat top wall and rigidly connected to the outer edge thereof by a series of circumferentially spaced webs, a disk of larger diameter than said shade and means for removably securing the flat top wall of said shade to the under side of said disk, said disk having a bottom surface adapted to reflect light issuing from the spaces between said circumferentially spaced webs, and the differently tapered portions of said shade having exterior surfaces adapted to reflect at different angles light reflected by said bottom surface of said disk.

DAVID J. BILLER.
